UNITED STATES PATENT OFFICE.

HORACE B. SETZLER, OF COFFEYVILLE, KANSAS, ASSIGNOR TO THE NATIONAL REFINING COMPANY, OF CLEVELAND, OHIO, A CORPORATION OF OHIO.

PROCESS OF PRODUCING GASOLINE.

Application filed June 9, 1916. Serial No. 102,651.

My invention relates to an improved process of producing gasoline, and is herein exemplified as preferably practiced by the pressure distillation of gas-oil, under conditions causing the extraction of carbon therefrom. My object is to obtain a maximum yield of gasoline with a minimum production of gas and carbon, by a process that is substantially continuous, safe and commercial in all respects. This application is a continuation in part of my prior application Serial No. 57,358, filed October 22, 1915.

It is highly desirable to start with a distillate having known characteristics containing natural constituents, which under ordinary conditions, and known methods, distill over between temperatures of 450° F. and 675° F., commercially known as gas-oil, having a gravity of 32 to 34 Baumé. Primarily, my object is to obtain from said distillates, products which under ordinary conditions distill between temperatures of 80° F. and 350° F., and have a gravity of 56 to 60 Baumé; the properties of which are dissimilar to the properties of the natural constituents. To this end, I provide means for preventing the carbon, freed during the operation, from settling, concentrating and depositing in a semi-crystalline coke form, on the sheets of the still.

Until comparatively recent times, the art of distilling petroleum, has consisted principally in separating its natural constituents, and grouping them into a series of products applicable for commercial use. Gasoline, kerosene, gas-oil, lubricating oil and wax, when separated by distillation, and each product grouped separately, constitute natural constituents found in the original mass of crude oil. Recently, however, it has become important commercially, to break down or "crack" certain of the natural hydrocarbons, as it has been termed, for the purpose of increasing the output of gasoline, by pressure distillation.

Distilling under pressure has for its object, the production of low boiling point hydrocarbons; the properties of which are dissimilar to the properties of the hydrocarbons from which they are obtained. Pressure distillation therefore, must not be confounded with the normal atmospheric distillation, because the product sought in

pressure distillation, is not a natural constituent of crude oil, but is a product obtained from the natural constituents, by its subjection both to pressure and heat. In known methods, the carbon produced by cracking the hydrocarbons, settles to the bottom of the still, and remains there; the particles growing in mass, concentrate themselves in a layer over the entire bottom. Their presence is dangerous, because of the fact that it is unsafe to operate a still under pressure with a layer of carbon upon its bottom. Therefore, it is quite essential to the continuing performance of such processes, that some device, or apparatus be provided, whereby the carbon, which splits off, is kept from depositing on the sheets of the still.

While my invention is not necessarily limited thereto, I may readily explain the practice thereof in the treatment of the commercial product of gas-oil; comprising a derivative hydrocarbon whose boiling point ranges between 450° and 675° F., with a specific gravity between 32 and 34 Baumé, as obtained from mid-continent crude oil. This is selected as typical and explanatory merely, since the temperatures and specific gravities of other derivatives, subjected to my process and even other gas oils, necessarily will vary materially.

The improved process of my invention, may best be explained in connection with the accompanying drawings, wherein:—

Fig. 1 is a diagrammatic view in side elevation, partially broken away, showing apparatus adapted for the practice of my invention.

Fig. 2 is a partial longitudinal section of a still equipped for practicing my invention, and

Fig. 3 is a view in cross-section thereof, on line 3—3 of Fig. 2.

Throughout the drawings, similar parts are indicated by the same character of reference.

The assembled treating apparatus is indicated in Fig. 1: comprising a firing chamber 1, equipped with suitable heating means, such as the gas burner 2, forwardly positioned therein beneath, the still. A down-draft flue 3, communicates with the heating chamber 4, intermediately positioned in advance of the chimney stack 5. The heat

from combustion is applied to the bottom of the horizontal cylinder-still 7, which is set over and supported by front and rear end walls, of the furnace and the combustion chamber. The still is provided with a gauge-glass 6, a manhole 8, a pressure gauge 9, and a thermometer 9'. A charging inlet pipe 10, enters the still at its top, near the front end; the charging being controlled by valve 11, past which oil is pumped through the preheating coils 4', by means of pump 12, receiving its supply from a tank not shown. An inclined vapor line 13, leaves the still near its rear end, and leads to air-condensing coils 14, and a condenser box. Beyond the condenser box is a valve 16, connected to a pipe leading to the receiving tank 17; the purpose of which equipment is to carry off, condense and receive the products which distill over. The inclined vapor line 13, is itself an air-cooler and is augmented by short angularly-extending members 13', which assist in condensing.

The still 7, is equipped with a revolving shaft 18, mounted in water-cooled stuffing boxes 19, and fitted with a pulley wheel 20. Inside the still, there is attached to the shaft, a double helicoidal cleaner 21, of such diameter and length as to engage the entire heated inner periphery of the still 7. At the front and rear ends of said shaft respectively, are water pipes 22, 22', leading from a source not shown, and entering passages drilled in the ends of the shaft 18, a distance equal, at least to the length of the shaft inside the stuffing boxes. A discharge pipe is attached to the still at its bottom, near the rear end, and to which is connected outlet pipe 24, leading through valve 25, to a cooling box 26, and thence through the pipes 27, inside the box, and out through a valve 28, to a receiving tank 29.

A motor 30" furnishes the power for driving the pulley wheel 20, connected to shaft 18. The double helicoidal scrapers preferably are augmented by loops of chains 21', which bear upon the bottom sheets of the horizontal still, and assist in preventing the adhesion of carbon.

With this description of convenient apparatus for practicing the same, I will now explain, a process typical of my invention. The cylinder still 7, is charged with gas oil, we may assume, having the characteristics previously explained, and to approximately one-half the full volume or capacity of the cylinder still; after which valves 11 and 16 are closed. Power is turned on the motor connected with pulley wheel 20, which rotates the helicoidal scraper or cleaner inside the still. The still is heated by the burner 2; the products of combustion being directed against the bottom of the still, so that the temperature of the contained oil, rapidly rises, until it has reached about 700° F., at

which temperature the pressure begins to rise, and is indicated on the pressure gauge 9.

By the time pressure has reached 40 to 60 pounds, the temperature will have risen to approximately 730° F., at which temperature and pressure, carbon begins to split off from the heated hydrocarbons; thereby producing new hydrocarbon compounds dissimilar from the gas-oil, and having boiling points of 80° to 350° F., and a Baume gravity of 56 to 58. It will be evident to those skilled in the art, that compounds having boiling points of 80° to 350° F., cannot, by reason of their inherent physical properties, remain in the still at the temperature referred to, hence they are permitted to pass out through the vapor line 13, and are condensed in the coil 15, and thence conducted to the tank 17, by control of the valve 16.

A suitable safety-valve 15' may be provided in the pressure line to relieve any excessive or dangerous pressure generated.

I have found that without the use of suitable cleaning, scraping, scouring or agitating means, carbon, at the instant it is freed from its previous combination; being in a nascent state of amorphous character, and settling out of the mass of gas-oil, seems to be attracted, or drawn to the heated bottom still sheet. Normally, these particles of carbon cohering together, and agglomerating over the bottom sheet, form a layer of carbon, assuming a semi-crystalline form, which would have the dangerous results heretofore explained. By using a helicoid cleaner, continuously revolving inside the still, and engaging the heated section of the inner periphery of the cylinder, or its equivalent, the carbon which has been freed from its combination, is retained in an amorphous condition, and suspended throughout the mass of oil. Any carbon, which by chance is attracted or becomes momentarily attached to the bottom, cannot remain there, because the blades of the helicoid and chains engaging the bottom, sweep the particles of carbon away in their course of travel.

In addition, the helicoid performs several advantageous functions. It is slowly revolved, and in a direction carrying the gas-oil from the front to the rear of the still. Being in constant contact with the heated bottom sheets, said helicoid becomes highly heated and serves to distribute the heat throughout the interior of the still;—and thus the heat is communicated directly to the vapors in said space above the gas oil, as well as to the fluid itself; thereby greatly facilitating the practice of my improved process. It has catalytic action, as well.

Hydrocarbons ultimately may be degraded down to permanent gases and solid carbon

by the influence of heat, and by the proper regulation of the same, intermediate products between carbon and permanent gases, can be produced, but as far as I am aware, 5 no device or apparatus previously has been employed to extract and maintain the carbon in an amorphous condition, while the process is progressing. It is apparent then, that the degradation or decomposition of 10 hydrocarbons, necessarily means the extraction of carbon, which is the clogging element in the successful performance of any pressure operation. This I have overcome by the means referred to, and in addition, by 15 suitably controlling the re-action, I produce a minimum, both of carbon and fixed gas.

In practicing my process, the gas-oil or other hydrocarbon supplied to the still, is subjected to high temperatures and moderate pressures, and the chemical affinity of 20 its elements being partially overcome, certain of the combined carbon atoms are split off in amorphous condition, and are maintained, in that condition by continued agitation. When the chemical affinity between the carbon and hydrogen has been broken, the existing chain of hydrocarbons is opened, and a new series is produced, which cannot remain in the highly heated still, because of 25 their low boiling point. Consequently, they are permitted from time to time, to pass out through the vapor line.

After the described operation has progressed, until approximately 10% of the 30 volume of gas-oil charged into the still has been converted into other products boiling between 80° and 350° F., and the Baumé gravity of said products is found to range from 56 to 58, as indicated by the hydrometer on samples taken from the end of the 35 pipe entering tank 17, the pump 12 is started. Gas-oil is continuously pumped in through the heating coils 4', and the line 10, regulated by and through valve 11, entering the 40 still at the front end, at the same time the new products referred to, are conducted off through the vapor line 13. Any convenient device may be used, such as meters 30, 31, to establish the ratio of a constant quantity 45 of gas-oil, entering the still at the front end, and a corresponding quantity of products passing off, and collecting in the receiving tank 17.

Having established the quantity entering 50 and leaving the still, the operation is continued. The valve 25, connected by a pipe to the trap on the bottom, near the rear end of the still, is then operated for the purpose of drawing off the contents, either continuously or periodically; measuring it through a meter 32, after the liquid has passed through the coils 27, submerged in the cooling box 26.

In the instance assumed, the Baumé gravity of the oil in the still will have reached

approximately 24, at which gravity I begin to draw off the contents at the rear end of the still, but I wish it understood that the gravity test referred to is not invariable. The figures were used merely to indicate the 70 preferred mode of operation, and I have found, that with the gas-oil referred to, I can go lower, with no apparent deposit on its bottom, if the scouring action be continued, and the operation proceeds regularly 75 under these conditions.

From the foregoing it will be seen that the described process is capable of indefinite continuation, depending somewhat upon the character of the hydrocarbons treated. The 80 liquid condensed and collected in tanks 17, may be distilled in the ordinary manner, primarily for their gasoline content, while the heavier distillates therefrom, may be 85 remixed with the contents of tank 29, and reintroduced into the still 7, for further treatment, if desired. Connected with the intermediate tank 33 is a pressure gauge 30", which may be used for controlling the continued practice of the described process, but 90 as these steps form no part of my invention, they need not be further referred to herein.

It is apparent that the mechanism provided, serves continuously to agitate the contents of the still, and such agitation, moreover, is coupled with the repeated scouring and scraping of the bottom of said still; all 95 of which contribute to the retention of the carbon in its amorphous form, and prevent its adherence to the bottom plates of said 100 still. In addition, thereto, the helicoidal blades 21, may be formed of copper or copper alloy, instead of steel, and may be substituted or augmented by chains or brushes of any material, adapted to afford catalytic 105 action, and therefore promote the chemical re-actions within the still. These further features, however, as well as the precise apparatus herein described, form no essential part of my present invention. 110

Instead, my invention is concerned with the method of extracting carbon from hydrocarbons by their decomposition under conditions permitting the control of the reactions, whereby the existing chains of the 115 hydrocarbons are opened and a new series is produced. The process essentially consists in distilling a suitable hydrocarbon, preferably gas-oil, under a relatively low pressure, i. e., within a range of from 40 to 100 pounds, and at temperatures within a range of from 700° to 750° F. Meantime, the gas-oil is maintained at a substantially constant level within the still, by pumping in fresh and preferably preheated fluid, so 120 that there is approximately a pressure space within the still of half its volume. Throughout the entire process, the motion of the helicoid is continued for the purpose of scraping the bottom, carrying the heat 125

throughout the interior of the still, and gradually conveying the heavier hydrocarbons toward the discharging end of the still. This process, moreover, may well be augmented by the reflux of the lower boiling point hydrocarbons, from the vapor line into the still, so that they may be subjected to the carbon extracting or process of freeing the carbon above described, and obtain a maximum yield of hydrocarbons, from which commercial gasoline may be distilled.

The process herein described differs from any other with which I am acquainted, by reason of the fact that under favorable conditions, I have been able to produce a yield of from 40 to 50 per cent of gasoline, with the extraction merely of from 3 to 8 ounces of carbon, and the production of fixed gases approximating 20 to 30 cubic feet only per barrel of gas-oil. The preferred pressure approximates 60 pounds per square inch, and I have found that by maintaining the pressure relatively low, throughout the vapor line, that the yield of fixed gases is materially reduced, thereby augmenting the production of gasoline. The importance of the helicoid, as a member serving to maintain the heated bottom sheets free from carbon, conveying the treated hydrocarbon and extracted carbon toward the point of discharge, and distributing the heat through the fluid and vapor space within the still, can scarcely be over-estimated, inasmuch as the successful practice of the process is dependent thereon. However, I do not claim in my present application the scouring or abrading function of the helicoid per se, but I have included it only in connection with the recited series of attendant steps in the process of cracking, as respectively defined in certain of the claims.

Having now described in some detail, the process of my invention, as I preferably practice it, I claim as new, and desire to secure by Letters Patent, the following:

1. A process involving the separation of carbon from gas-oil to produce gasoline, which consists in subjecting the gas-oil to pressure-distillation in a volume maintained substantially constant under conditions in-

volving a pressure of from 50 to 100 pounds, temperatures of from 700° to 750° F., within a highly heated pressure space approximately equal to the volume of gas-oil under treatment; meanwhile subjecting the gas-oil to suitable means for concurrently scouring the bottom of the still, and advancing the treated hydrocarbons to the point of withdrawal, substantially as set forth. 60

2. A process involving the separation of carbon from gas-oil to produce gasoline, which consists in subjecting the gas-oil to pressure distillation in a volume maintained substantially constant under conditions involving a pressure of from 50 to 100 pounds, and temperatures of from 700° to 750° F., within a highly heated pressure space approximately equal to the volume of gas-oil under treatment; meanwhile maintaining a 65 supply of preheated gas-oil, and subjecting the treated gas-oil to a highly heated moving member serving to free the bottom of the still from carbon deposit, substantially as set forth. 75

3. A process for treating petroleum or its derivatives, which consists in conducting pressure distillation thereof under conditions insuring a relatively large pressure space in the container, mean time maintaining the freed carbon in finely divided state and suspension, while subjecting the treated derivatives and pressure space to the action of a highly heated moving member introducing a preheated supply of hydrocarbons 80 and withdrawing the newly formed hydrocarbons from the container, substantially as set forth. 85

4. A process involving the separation of carbon from gas-oil to produce gasoline, 90 which consists in heating it at temperatures approximating 700° F. under pressures adapted for cracking in a suitable still; meantime maintaining the freed carbon in a state of suspension, withdrawing the newly 95 formed hydrocarbons effecting the reflux of heavier distillate fractions and supplying proportionate quantities of gas-oil in pre-heated condition, substantially as set forth.

In testimony whereof I do now affix my 100 signature

HORACE B. SETZLER.
